(**) Term: **14 Years**

The ornamental design for a touch screen pen for electronic device with camera function, as shown and described.

(21) Appl. No.: **29/346,656**

DESCRIPTION

(22) Filed: **Nov. 4, 2009**

FIG. 1 is a perspective view of a touch screen pen for an electronic device with camera function, showing the touch screen pen in a folded touching mode in which the touch screen pen is capable of contacting a touch screen of the electronic device.

(30) **Foreign Application Priority Data**

Jun. 18, 2009 (CN) 2009 3 0306488

FIG. 2 is similar to FIG. 1, but showing the touch screen pen in an unfolded supporting mode in which the touch screen pen is capable of supporting the electronic device.

(51) **LOC (9) Cl.** **14-02**

FIG. 3 is a front view of the touch screen pen in the unfolded supporting mode.

(52) **U.S. Cl.** **D14/411; D16/244**

FIG. 4 is a rear view of the touch screen pen in the unfolded supporting mode.

(58) **Field of Classification Search** D8/61;

FIG. 5 is a left side elevational view of the touch screen pen in the unfolded supporting mode.

D14/411, 431, 404, 390; D19/35, 36, 41–51,
D19/54–58; 401/99, 100, 104–107; 345/179,
345/173; 178/19.01, 19.03; 700/94; D21/330;
715/863; D16/244

FIG. 6 is a right side elevational view of the touch screen pen in the unfolded supporting mode.

See application file for complete search history.

FIG. 7 is a top plan view of the touch screen pen in the unfolded supporting mode; and,

(56) **References Cited**

FIG. 8 is a bottom plan view of the touch screen pen in the unfolded supporting mode.
